(57) **CLAIM**

The ornamental design for a cartridge for skin treatment apparatus, as shown and described.

DESCRIPTION

FIG. 1 is a front, right side perspective view of a cartridge for skin treatment apparatus showing our new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; and, FIG. 8 is a perspective view in combination with a skin treatment apparatus. The broken line showing of the skin treatment apparatus is provided for the purpose of illustrating environmental structure and forms no part of the claimed design. The broken lines indicate portions of the article that form no part of the claimed design.

1 Claim, 8 Drawing Sheets
